(57) **CLAIM**

The ornamental design for a primer diverter cup used in polymer ammunition, as shown and described.

DESCRIPTION

FIG. 1 is an isometric view of a primer diverter cup showing my new design.

FIG. 2 is a top view of a primer diverter cup showing my new design.

FIG. 3 is a cross sectional view of a primer diverter cup showing my new design.

FIG. 4 is a side view of a primer diverter cup showing my new design.

FIG. 5 is a side view of a primer diverter cup showing my new design.

FIG. 6 is a bottom view of a primer diverter cup showing my new design; and,

FIG. 7 is an isometric cross sectional view showing a cartridge base insert molded into a cartridge casing and the primer diverter cup inserted in the primer recess.

The broken line showing of a shell casing in FIG. 7 is included for the purpose of illustrating environment and forms no part of the claimed design.

The nature and intended use of the article in which the design is embodied is a primer diverter cup for use in a primer insert used in the manufacture of polymer ammunition casings.
